FOREIGN PATENT DOCUMENTS

WO WO-2023045777 A1 * 3/2023

Primary Examiner — Patricia A Palasik(74) *Attorney, Agent, or Firm* — LADAS & PARRY LLP(57) **CLAIM**

The ornamental design for a carrying unit of warehouse robot as shown and described.

DESCRIPTION

FIG. 1 is a first perspective view of a carrying unit of warehouse robot showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken line portions of the carrying unit of warehouse robot in the drawings form no part of the claimed design.
